SPARK PLUG INSULATORS CONTAINING
STANNIC OXIDE

Harry G. Schurecht, Detroit, Mich., assignor to Champion Spark Plug Company, Toledo, Ohio, a corporation of Delaware

No Drawing. Application July 28, 1958
Serial No. 751,175

6 Claims. (Cl. 106—46)

This invention relates to spark plug insulators containing stannic oxide, and, more particularly, to such insulators produced by firing particular compositions of oxide or oxide-forming materials including stannic oxide.

The use of tin oxide in making different refractory bodies has previously been suggested, for example, bodies suitable for use in contact with molten glass, and bodies having a high dielectric constant (in excess of one thousand in all instances) suitable for use as electro-mechanical devices such as piezo electric crystals.

Ceramic insulators having a dielectric constant greater than about 10 are completely unsuited for spark plug uses. Relatively high voltages are conducted interiorly through the electrode system of spark plug insulators. The air surrounding such insulators is ionized to a substantial extent by this electric current. The ionization of the air surrounding the insulator provides a potential path for spark discharge, for example from the metal connection at the top of an ordinary automotive spark plug to the grounded portion of the spark plug, or to a metallic component of an associated automobile engine. When the dielectric constant of the insulator is as high as about 10 such ionization occurs to an extent sufficient that discharge in this manner occurs to the exclusion of the desired discharge across the spark gap of the plug. Ceramic insulators can be produced from pure stannic oxide and also from mixtures of stannic oxide with minor amounts of fluxing ingredients. Such insulators, however, have properties which make them completely unsuited for use as spark plug ceramics. For example, a spark plug insulator is subjected to high temperatures in service, and must be effective at such high temperatures, as well as at low temperatures which are encountered in a cold engine and all intermediate temperatures. To be suited for spark plug use, a ceramic, in the form of a cylinder about $\frac{1}{2}$ " in diameter and approximately $\frac{1}{2}$ " in length must have an electrical resistance, at 1350° F. and at lower temperatures, of at least 1 megohm. Since it is a general characteristic of ceramic materials that their resistance decreases with increases in temperature, a particular ceramic can be shown to be suitable for spark plug use by determining that a cylinder thereof of the indicated size has an electrical resistance of at least 1 megohm at a temperature of 1350° F. or higher, or a given ceramic can be shown to be unsuited for spark plug use by a determination that such a cylinder thereof has a resistance of less than 1 megohm at a temperature of 1350° F. or lower. It has been determined that such a cylinder produced from pure stannic oxide or from a mixture of 96.5 parts of stannic oxide with 1.5 parts of whiting, 2.0 parts of talc and 1.5 parts of bentonite has a resistance of less than 0.1 megohm at a temperature of 1000° F. Neither of such insulators, therefore, is suited for spark plug use. This suggests that stannic oxide would be an undesirable constituent in a ceramic batch for use in the preparation of a spark plug insulator because stannic oxide in an appreciable amount would be expected to

2

have an undesirable effect upon electrical resistance, at least at elevated temperatures.

The terms "percent" and "parts" are used herein and in the appended claims to refer to percent and parts by weight, unless otherwise indicated.

The present invention is based upon the discovery that it is possible to produce sintered ceramic spark plug insulators by firing mixtures consisting essentially of alumina and stannic oxide, in certain proportions, and 10 that the resulting insulators not only have the dielectric properties requisite for spark plug use, but also have thermal conductivity characteristics which are at least equivalent to presently used spark plug ceramics, and are resistant to corrosion by compounds of lead and other chemicals which are present in the firing chambers of present-day internal combustion engines.

According to the invention, a sintered ceramic spark plug insulator is provided. Such an insulator is produced by firing a blend of refractory materials consisting 20 essentially of from about 19 parts to about 81 parts of SnO_2 and from about 81 parts to about 19 parts of Al_2O_3 . Insulators produced from such blends have the previously indicated properties, and limited amounts of other materials can be added to the blends, as will subsequently be discussed in more detail, without appreciably affecting such properties of insulators which are produced therefrom.

The suitability of various compositions consisting of stannic oxide and alumina, in proportions as set forth 30 above, for use in the manufacture of electrical insulators for spark plug purposes was demonstrated by preparing several insulators, and testing the properties of each. Representative examples of such compositions, and the properties of insulators produced therefrom, are given in 35 the following example, which, like the subsequent example, is to be construed as illustrative only, and not as limiting the invention.

EXAMPLE 1

40 Several blends consisting of stannic oxide and alumina were wet milled to substantial uniformity (usually for 18 hours), and were then dried and mixed with 4 percent of paraffin wax, based upon the weight of dry ingredients, dissolved in carbon tetrachloride. The wax 45 was thoroughly mixed with the dry ingredients, and the carbon tetrachloride volatilized, leaving the wax uniformly dispersed throughout the composition. Test cylinders about $\frac{1}{2}$ " in diameter and approximately $\frac{1}{2}$ " in length were then pressed from each mixed composition, 50 using a total pressure of 10,000 pounds. The cylinders were then fired to Cone 31.

The bodies so prepared were tested to determine their suitability for use as spark plug insulators. The electrical resistance of the $\frac{1}{2}$ " cylinders was determined at 55 1200° F. or 1400° F., and, in some instances, at 1500° F. As has been indicated above, a ceramic body having a resistance (when in the form of such a cylinder) of at least 1 megohm at 1350° F. or higher is considered satisfactory for spark plug purposes. In addition, an 60 insulator having a resistance of at least about 10 megohms at 1200° F. is considered satisfactory for spark plug purposes.

Another standard test was conducted to compare the thermal diffusivities of insulators produced from the 65 different compositions: The test involved placing a crystal of citric acid on one end of the sintered $\frac{1}{2}$ " cylinder, and immersing the other end of the cylinder in a 600° F. metal bath to a depth of about $\frac{1}{8}$ ". The number of seconds required for heat conducted through the insulator to melt the citric acid crystal, which melts at 307.4° F., is reported in the tables herein as "thermal diffusivity," 70 and is an inverse function of thermal conductivity. To

be at least comparable with presently used spark plug insulators in this respect, a ceramic insulator should have a thermal diffusivity, so measured, not greater than

herein, entries under the heading "Dye Test" are "Mat," which means matured; "U.F.," which means underfired, and "SUF," which means slightly underfired.

Table I

Body No.	Composition in Parts		Electric Resistance (Megohms)			Thermal Diffusivity Time in Seconds	Dye Test
	Al ₂ O ₃	SnO ₂	1,200° F.	1,400° F.	1,500° F.		
1	77.2	19.3	80	20	10.5	18.8	U.F.
2	57.9	38.6	65	20	10	19.5	U.F.
3	38.6	57.9	10	-----	-----	17.3	U.F.
4	19.3	77.2	40	12.8	-----	20.9	U.F.

about 30 seconds. Ideally, a ceramic body should have a thermal diffusivity not greater than about 20 seconds.

A low thermal diffusivity time, or a high thermal conductivity, is an important characteristic of a spark plug insulator. In service, such an insulator is subjected to high temperatures in the firing chamber of an internal combustion engine. The insulator is heated to some temperature which depends, in the main, upon the mean effective firing chamber temperature, the thermal conductivity of the ceramic insulator and the design of the ceramic insulator and of the spark plug of which it constitutes a part. In general, high output present-day engines, when operated at or near full load, necessitate the use of spark plugs having thermal diffusivity times of 30 seconds or less in order to avoid heating of the ceramic insulator, in service, to a temperature sufficiently

20

25

30

EXAMPLE 2

Table II, below, presents typical test results obtained with bodies produced from blends consisting essentially of Al₂O₃ and SnO₂ in the previously indicated proportions. It will be observed from the results presented in Table II that substantial amounts of ZrO₂ can be employed in a blend used to produce an insulator according to the invention without adversely affecting the desirable characteristics of electrical resistance at elevated temperature and thermal diffusivity, and that limited amounts of whiting, talc and bentonite can be similarly added without adverse effect. All of the bodies reported in Table I, above, and in Table II, below, have been tested and found to be unexpectedly resistant to corrosion by lead and other compounds which are usually present in automotive and aviation fuels.

Table II

Body No.	Composition in Parts						Thermal Diffusivity Time in Seconds	Electric Resistance (Megohms)			Dye Test
	Al ₂ O ₃	SnO ₂	ZrO ₂	Whiting	Talc	Bentonite		1,200° F.	1,400° F.	1,500° F.	
5	57.9	19.3	19.3	-----	-----	-----	23.8	48	36	15	SUF
6	57.9	19.3	19.3	1.5	2.0	1.5	22.9	100	23	-----	Mat.
7	38.6	38.6	19.3	-----	-----	-----	29.4	40	-----	-----	U.F.
8	19.3	57.9	19.3	-----	-----	-----	30.6	30	-----	-----	U.F.
9	19.3	38.6	38.6	1.5	2.0	1.5	27.8	11.5	-----	-----	Mat.
10	77.2	19.3	-----	1.5	2.0	1.5	18.6	100+	100+	100+	Mat.
11	57.9	38.6	-----	1.5	2.0	1.5	18.3	100+	50	38	Mat.
12	38.6	57.9	-----	1.5	2.0	1.5	17.8	45	3.1	-----	SUF

high that it will cause premature ignition of a fuel-air mixture. Insulators having thermal diffusivity times of 20 seconds or less are ideal for use in such engines because more latitude is given a spark plug engineer in designing a plug which will operate satisfactorily without causing such premature ignition.

The insulators produced as described above were also subjected to tests to determine the adequacy of firing. The test involved application to each insulator of a dye solution, and visual examination of the so-treated insulator for evidence of dye absorption. Any insulator which absorbed dye was considered to be underfired, meaning that a higher firing temperature should be used, or that some fluxing material should be mixed with the composition to enable maturation under Cone 31 firing conditions. Insulators which did not absorb dye were either matured or overburned. These two states were distinguished by a specific gravity test, insulators having the highest specific gravity being properly matured and insulators which did not absorb the dye solution, but which had a lower specific gravity, being overfired.

Typical test results for bodies produced from blends consisting of alumina and stannic oxide, in the proportions indicated above, are presented in Table I, below. In Table I the composition of each blend is given, as well as the thermal diffusivity time, measured as discussed above, the electrical resistance at one or more of the indicated elevated temperatures, and, under the heading "Dye Test," the result of the above-described test for adequacy of a Cone 31 firing. ticizer and binder, is preferably employed in producing an insulator according to the invention, and, most desirably, to the extent of from about 1 percent to about 2 percent, based upon the total weight of the blend, or ceramic batch. Both whiting and talc, as used in the blends or batches used in preparing the bodies reported in Table II, above, act as fluxes, tending to reduce the cone number designation of the firing required to effect maturation. Such a flux, or a different flux, is preferably employed in producing an insulator according to the invention, and, most desirably, to the extent of from about 1 percent to about 5 percent, based upon the total weight of the blend or ceramic batch. It is also preferred that the flux include an alkaline earth compound which, after firing, is in the form of the oxide, and most desired that it include, in addition to the alkaline earth compound, a magnesium silicate.

While reference has been made herein to stannic oxide, or SnO_2 , as well as to alumina, or Al_2O_3 , other tin oxides can be used in place of stannic oxide, or other tin compounds which revert to an oxide during firing, or compounds other than alumina which revert to alumina during firing can similarly be employed. Substantially the same properties result in the completed insulator. In addition, an entire insulator can be produced from a blend, as is disclosed in detail in the foregoing examples, or only a portion thereof can be produced from the blend, for example the firing tip, or the surface of the firing tip.

This is a continuation-in-part of application Serial No. 371,073, filed July 29, 1953, which was, in turn, a continuation-in-part of application Serial No. 69,409, filed January 5, 1949, both now abandoned.

It will be apparent that various changes and modifications can be made from the specific details set forth herein without departing from the spirit and scope of the attached claims.

What I claim is:

1. A ceramic spark plug insulator, at least the surface of which, at the firing end, is produced by sintering a blend consisting essentially of from about 19 parts to about 81 parts of SnO_2 , and from about 81 parts to about 19 parts of Al_2O_3 .

2. A ceramic spark plug insulator, at least the surface of which, at the firing end, is produced by sintering a blend consisting essentially of from about 19 parts to about 81 parts of SnO_2 , and from about 81 parts to

about 19 parts of Al_2O_3 , and including, in addition, based upon the total weight of the blend, from about 1 percent to about 5 percent of a flux.

3. A ceramic spark plug insulator, at least the surface of which, at the firing end, is produced by sintering a blend consisting essentially of from about 19 parts to about 81 parts of SnO_2 , and from about 81 parts to about 19 parts of Al_2O_3 , and including in addition, based upon the total weight of the blend, from about 1 percent to about 5 percent of a flux comprising an alkaline earth compound which, after firing, is in the oxide form.

4. A ceramic spark plug insulator, at least the surface of which, at the firing end, is produced by sintering a blend consisting essentially of from about 19 parts to about 81 parts of SnO_2 , and from about 81 parts to about 19 parts of Al_2O_3 , and including, in addition, based upon the total weight of the blend, from about 1 percent to about 5 percent of a flux comprising a magnesium silicate and an alkaline earth compound which, after firing, is in the oxide form.

5. A ceramic spark plug insulator, at least the surface of which, at the firing end, is produced by sintering a blend consisting essentially of from about 19 parts to about 81 parts of SnO_2 , and from about 81 parts to about 19 parts of Al_2O_3 , and including, in addition, based upon the total weight of the blend, from about 1 percent to about 5 percent of a flux comprising a magnesium silicate and an alkaline earth compound which, after firing, is in the oxide form, and from about 1 percent to about 2 percent of a plasticizer.

6. A ceramic spark plug insulator, at least the surface of which, at the firing end, is produced by sintering a blend consisting essentially of from about 19 parts to about 81 parts of SnO_2 , and from about 81 parts to about 19 parts of Al_2O_3 , and including, in addition, based upon the total weight of the blend, from about 1 percent to about 5 percent of a flux comprising a magnesium silicate and an alkaline earth compound which, after firing, is in the oxide form, and from 1 percent to 2 percent of bentonite.
